Inventor
C. V. Boys
by Marksville Aug.

UNITED STATES PATENT OFFICE.

CHARLES VERNON BOYS, OF WESTMINSTER, LONDON, ENGLAND.

HEAT INTERCHANGER.

Application filed October 24, 1924, Serial No. 745,719, and in Great Britain January 3, 1922.

My invention relates to heat interchangers and has for its object to provide improved constructions which are particularly applicable to the instrument described in my prior 5 application Serial No. 440,453.

Referring to the accompanying diagrammatic drawings:—

Figure 1 represents a vertical sectional view of a convenient construction in accordance with the present invention, 10

Figure 2 is a plan view partly in section on the line 2—2 of Figure 1 corresponding thereto, and Figure 3 is an inverted section on the line 3—3 of Figure 1.

15 In carrying the invention into effect in one form by way of example as indicated in Figures 1 and 2, the heat interchanger is made of sheet metal (preferably of lead) autogenously soldered for continuously re- 20 cording calorimeters, but other metals such as copper or brass soft soldered might be used for instruments not in continuous use. Lead autogenously soldered is well known to resist the destructive action of the sul- 25 phurous vapours of burning gas and so is preferable more especially for continuous use.

It will be evident that other material than metal which can be made into sheets and 30 joined and which is sufficiently heat-conducting and incorrodible might be used for the interchanger.

The heat interchanger is formed of sheet metal bent or folded so as to contain numerous narrow up passages *a*, *b*, *c*, *d*, for the 35 circulating water and a voluminous up passage *x* and down passages *e* for the gases of combustion.

40 In Figure 2 the metal of the heat interchanger is shown as part of a single strip of thin sheet metal bent backwards and forwards radially so as to enclose the narrow waterways *a* between its own folds and to form an additional waterway *b'* between these and the casing *f* in which the inter- 45 changer is contained. At the upper and lower ends of said heat interchanger the radial waterways *d* and *c* respectively are somewhat widened as indicated so that there 50 may be a sufficient water circulation up the inner folds of the metal. These inner folds are arranged to be in contact (Figure 2) or nearly so, in order that the ascending gases in passage *x* and the descending gases in 55 passages *e* may not intermix, and any accidental chinks left between these will in

use be stopped by condensed vapour. Below the slight widenings of the radial waterways at the lower end the folds are pinched together and soldered together and 60 the outermost parts are bent inwards at *g* sufficiently for the interchanger to be driven into the ring *h* and soldered thereto.

At the upper end of the interchanger the outermost parts are bent inwards, the radial 65 webs are cut off at an angle as shown in Figure 1 and are there pinched together and soldered at *j*, so that rising water can escape upwards and outwards in the numerous narrow passages between the bent-in portions 70 as indicated by the arrows on the right of the centre of Figure 1.

The interchanger is shown as contained within a cylindrical casing *f* to which a flange *q* is permanently secured. The 75 flange *h* is clamped to this flange *q* in a watertight manner through the intermediary of a washer *r* and clamping screws *s*. Water is admitted through the conduit *t* whence it circulates around the annulus *u*. 80

Three or more of the radial webs are carried higher than the rest to form supports *k*. These supports serve to carry a flat dome of fused silica or equivalent material *m* which in use becomes hot enough to prevent water 85 from condensing upon it, and as it is incorrodible, pimples of corroded metal immediately above the flame cannot be formed. Where these hot gases impinge directly upon water cooled metal, condensation of vapour 90 occurs and if the metal corrodes and forms a pimple the condensed vapour drops upon the burner *w* and puts out the flame.

Immediately above the silica dome *m* a metal dome or cap *n* is provided and this is 95 soldered all round as shown at *o* to the bent-in portions aforesaid, and thus the hot gases are able to move outwards and downwards as indicated by the arrows on the left of the centre of Figure 1 and the water is able to move upwards, but is not able to enter into the passages for the gases.

As will be seen at *p*, Figure 2, the two ends of the strip of sheet metal are bent inwards into one of the down gas passages and 100 there soldered together.

By the construction described above I am able to obtain a heat interchanger of great simplicity and cheapness of construction with a very large surface for the cooling 110 of the gases so that it may be made compact and it is durable if made of lead.

A further advantage is the very small water content and the large cross-section of the down gas-ways.

I have shown one form of bent sheet metal interchanger, but it is evident that such an interchanger having the special features and advantages described may be made in many forms and in two or more parts, but I claim all such constructions as equivalents.

10 Having now described my invention what I claim as new and desire to secure by Letters Patent is:—

15 1. A heat interchanger including a sheet of metal folded alternately inwardly and outwardly, so as to form a separating wall between a central uptake, a plurality of downcomers and a plurality of uptakes, means establishing communication between the said central uptake and plurality of 20 downcomers whereby said uptake and down-

comers constitute one conduit system, while the said plurality of uptakes constitute a separate conduit system.

2. A heat interchanger including a sheet of metal folded alternately inwardly and outwardly, so as to form a separating wall between a central uptake, a plurality of downcomers and a plurality of uptakes, means establishing communication between the said central uptake and plurality of 25 downcomers whereby said uptake and downcomers constitute one conduit system, while the said plurality of uptakes constitute a separate conduit system, a roof and an incorrodible element having a concave lower 30 surface disposed beneath and out of contact with said roof.

In testimony whereof I have signed my name to this specification.

CHARLES VERNON BOYS.
